UNITED STATES PATENT OFFICE.

HENRY A. WEIHMANN, OF PHILADELPHIA, PENNSYLVANIA, ASSIGNOR TO
SIMONS, BROTHER & CO., OF SAME PLACE.

DESIGN FOR A CANE OR UMBRELLA HANDLE.

SPECIFICATION forming part of Design No. 19,988, dated July 1, 1890.

Application filed April 15, 1890. Serial No. 348,082. Term of patent 3½ years.

To all whom it may concern:

Be it known that I, HENRY A. WEIHMANN, a citizen of the United States, residing in Philadelphia, in the county of Philadelphia and 5 State of Pennsylvania, have invented and produced a new and original Design for Cane or Umbrella Handles, of which the following is a specification, reference being had to the accompanying drawing, forming part thereof.

10 In the drawing is shown an elevation of a cane or umbrella handle embodying my new design.

A is the body part, and extends up for a considerable distance and then turns over in 15 more or less of an enlarged crook B. The head from the base D gradually increases in size as it extends upward to the end of the crook, and is made up of a series of gradually-increasing ribbed portions C C, all of

which are more or less curved, passing around 20 one side of the body part and under the crook and terminating in a line extending along the upper part of the crook and the other side of the body part.

The handle is made of any suitable mate- 25 rial.

Having now described my new design, what I claim as new, and desire to secure by Letters Patent, is—

The design for an umbrella or cane handle, 30 substantially as herein described and shown.

In testimony of which invention I have hereunto set my hand.

HENRY A. WEIHMANN.
